UNITED STATES PATENT OFFICE.

JAMES OLIVER KAFADER, OF FORT BIDWELL, CALIFORNIA.

HYDRAULIC RAM.

1,383,143.

Specification of Letters Patent. Patented June 28, 1921.

Application filed August 16, 1918. Serial No. 250,260.

To all whom it may concern:

Be it known that I, JAMES OLIVER KAFADER, a citizen of the United States, and a resident of Fort Bidwell, in the county of 5 Modoc and State of California, have invented a new and Improved Hydraulic Ram, of which the following is a description.

My invention relates to hydraulic rams and although capable of a wider use is more 10 particularly intended for installation in connection with subterranean water strata at different levels.

The general object of my invention is to provide a hydraulic ram adapted to be installed in a cased well extending between 15 subterranean strata that is the upper and lower levels of rise of the water in a well.

Another important object of my invention is to provide a hydraulic ram in which 20 the impetus valve will be so controlled as to cause the valve to be positively lifted to effect the intermittent opening thereof for the discharge of the motive column beyond the air chamber of the ram, as well as to 25 provide a lift means for the impetus valve extending to the top of the well in which the ram is installed and adapted to be adjusted to insure the opening and closing of the valve as well as its proper timing with 30 the discharge of the water through the ascension pipe.

Reference is to be had to the accompanying drawings forming a part of this specification, it being understood that the drawings are merely illustrative of one example 35 of the invention.

Figure 1 is a vertical section of a ram installed in a cased well between two indicated subterranean water strata;

40 Fig. 2 is an enlarged side elevation of the equalizer controlling the lift for the impetus valve;

Fig. 3 is a fragmentary view showing in side elevation the valved fitting at the lower 45 end of the ram and connecting the drive pipe with the air chamber, the view being taken in a plane indicated by the line 3-3, Fig. 1;

Fig. 4 is a cross section at the base of the 50 air chamber, the section being taken in a plane indicated by the line number 4 in Fig. 1.

In carrying out my invention in accordance with the illustrated example the ram is 55 installed in a well casing 10 extending be-

tween an upper subterranean water stratum A and a lower stratum A'. The drive pipe 11 of the ram in which the hydrostatic column or motive column is produced is suspended from the closed upper end 10^a of the well casing, said pipe being open for the inflow of water from the stratum A. The drive pipe 11 is secured at its lower end to a fitting 12 having a branch 13 leading to the air chamber 14 from which the ascension pipe 15 rises, the inlet to the air chamber from the passage 13 being controlled by a check valve 16 in the usual manner. The ascension pipe 15 extends through the top 10^a of the well casing and rises above the 70 ground level.

The impetus valve 18 in my improved ram instead of opening downwardly as usual in hydraulic rams, lifts in the opening movement and closes by a downward movement. The seat 17 of the impetus valve is in the fitting 12 directly in line with the vertical drive pipe 11 and has a stem 19 extending upwardly through said drive pipe and above the ground level. The upper end 80 of the valve stem 19 is connected with one end of an equalizer bar 20 pivoted between its ends in any suitable manner as on a standard 21 and the opposite end of the lever is subject to a retractile spring 22 secured to the base 21^a of the standard, the upper end of the spring engaging a threaded hook 23 having a wing nut 23^a or the like to raise or lower said hook for varying the tension of the spring. A set screw 24 in 85 the equalizer bar 20 is adapted to bear against a stop 25 on the standard 21 to limit the movement of said bar 20 in one direction under the action of the spring 22.

With the described construction in accordance with the principle of hydraulic rams, the impetus valve 18 will be closed by the flow of the motive column in the drive pipe 11 but the tension of the spring 22 will be sufficient to lift the said valve 100 and open the same upon cessation of flow of the motive column following a discharge into the air chamber 14. Thus, upon each period of rest of the motive column, the pressure of the spring will lift the impetus 105 valve permitting discharge of water therefrom beyond the air chamber and cause the intermittent discharge into the air chamber in the well-known manner of hydraulic rams generally. Thus, the positive opening of 110

the impetus valve is insured and consequently a proper operation of the ram generally, the spring-acted equalizer being readily accessible at the ground level to effect 5 any necessary adjustment. Also, the arrangement lends itself to installation between subterranean water strata.

A vent pipe 26 extends through the top 10^a of the well casing 10 for the intake or 10 escape of air due to the rising or falling of water in the well casing by the discharge through the fitting 12 by the opening of the valve 18.

I would state in conclusion that while 15 the illustrated example constitutes a practical embodiment of my invention, I do not limit myself strictly to the mechanical details herein illustrated, since manifestly the same can be considerably varied without departure from the spirit of the invention as 20 defined in the appended claims.

Having thus described my invention, I claim as new, an desire to secure by Letters Patent:

25 1. A hydraulic ram including a drive pipe having an open upper end and adapted to form a hydrostatic motive column, a valve-controlled air chamber communicating with said drive pipe, an ascension pipe rising 30 from the air chamber, an impetus valve controlling the intermittent discharge of said drive pipe beyond the air chamber and adapted to be closed by the flow of the motive column, said valve opening upwardly, and 35 spring actuated means to positively lift said valve, said lift means being subject to a cessation of flow of the motive column; together with a well casing adapted to be installed between upper and lower subterranean water 40 strata, said casing having its upper end closed and from which closed end said drive pipe is suspended and through which the

ascension pipe extends, said lift means being arranged above the well casing.

2. A ram including a drive pipe having 45 an open upper end, an air chamber communicating with said drive pipe, an ascension pipe rising from the air chamber, a well casing adapted to be installed between upper and lower subterranean water strata, said casing having its upper end closed and from which closed end the drive pipe is suspended and through which the ascension pipe extends, an impetus valve controlling the discharge from the drive pipe 50 below the connection of the air chamber, said valve opening upwardly, a stem carrying said valve and extending upwardly through said drive pipe and above the well casing to be located above the ground level, 55 an adjustable spring-pressed equalizer means connected with the valve stem and adapted to lift the valve to open the same upon a cessation of flow of the hydrostatic column in the drive pipe, and a vent pipe 60 extending through the closed upper end of the casing.

3. In a hydraulic ram, a casing having its upper end closed and adapted to be installed between upper and lower subterranean water strata, a pipe suspended 70 from the closed upper end of the casing and having an open upper end, a valve casing at the lower end of the pipe and having a valve seat and a branch member, an air 75 chamber secured to the branch member, a valve in the bottom of the air chamber, a discharge pipe leading from the air chamber out through the top of the casing, a valve in said valve casing a spring actuated 80 member at the ground level, and a rod connecting the said member with the last named valve.

JAMES OLIVER KAFADER.
